UNITED STATES PATENT OFFICE.

EARLE KEITH LYONS, OF SAN ANTONIO, TEXAS, ASSIGNOR TO DELAWARE PUNCH COMPANY OF AMERICA, OF SAN ANTONIO, TEXAS, A CORPORATION OF DELAWARE.

DESIGN FOR A BOTTLE.

Application filed June 16, 1927. Serial No. 22,452. Term of patent 14 years.

To all whom it may concern:

Be it known that I, EARLE K. LYONS, a citizen of the United States, residing at San Antonio, in the county of Bexar and State of Texas, have invented a new, original, and ornamental Design for a Bottle, of which the following is a specification, reference being had to the accompanying drawing, forming part thereof.

I claim:

The ornamental design for a bottle as shown.

EARLE KEITH LYONS.
